UNITED STATES PATENT OFFICE.

JOHN J. BAHUZKY, OF CHICAGO, ILLINOIS.

WINDOW OR DOOR LOCK.

Application filed July 16, 1921. Serial No. 435,247.

To all whom it may concern:

Be it known that I, JOHN J. BAHUZKY, a citizen of the United States, and resident of Chicago, county of Cook, and State of Illinois, have invented certain new and useful Improvements in Window or Door Locks, of which the following is a specification, and which are illustrated in the accompanying drawings, forming a part 10 thereof.

The invention relates to latches for window devices, the principal object of the invention being to provide an improved latch adapted to be secured to a window or door for effectively holding the same from movement in one direction from any position against any force which may be exerted to the end without interfering with movement in the opposite direction, but which may be readily adjusted to and firmly held in an inoperative position to permit free movement of the door or window in either direction. A further object of the invention is to provide such a latch which shall be easily and cheaply manufactured and readily applied for use on any type of door or window.

In the accompanying drawings:

Fig. 1 is a top plan view of the latch showing the same applied to the lower sash of a window, a detail of the upper sash being shown in section and the latch engaging member being in its retracted or inoperative position;

Fig. 2 is a sectional view taken on the line 2—2 of Fig. 1;

Fig. 3 is a view similar to Fig. 2, but showing the movable part of the latch in operative position;

Fig. 4 is a vertical cross section taken on the line 4—4 of Fig. 2;

Fig. 5 is a side elevation of the latch;

Fig. 6 is a front view of a window showing the latch attached to one of the sashes;

Fig. 7 is a front view showing the latch attached to a swinging door of ordinary construction;

Fig. 8 is a front view showing two of the latches applied to a sliding barn door, one being secured thereto at the top of the door and the other at the bottom.

In Figs. 1 to 6 the latch 10' is shown as secured to the lower sash 10 of a window whose upper sash is represented by the numeral 11. The latch consists of a housing 12 preferably stamped out of a single piece of metal and secured to the sash 10 as by

screws 12'. A sash engaging member 13 is eccentrically mounted on a rod 14 which is journaled in the housing 13, its ends projecting beyond the same, as at 15 and 16. A lever 17 preferably integral with the rod 14 is located at the end 15 and serves to move the member 13 into or out of operative position.

The opposite end 16 is slotted, as at 26 to enable the rod to be secured in inoperative position by means of a pivoted latch 25, accidental removal of which is prevented by a locking lug 27. In the position shown in Fig. 2, the sash 11 may be raised and lowered at will. As shown in Fig. 3 lowering the sash is prevented by the engagement of the sash engaging member 13, owing to its eccentric mounting. Preferably the member 13 comprises a metal block 19 in the form of a sector of a disk having secured within a groove 20, formed in its curved face, a corrugated strip 21, preferably of indurated composition fabric or hard rubber which tightly grips the sash 11, so as to prevent any slipping of the same. It is desirable to hold the sash engaging member normally in operative position and to accomplish this there is provided a light spring 22 reacting between a recess 23 in the block 19 and a stud 24 projecting inwardly from the housing 12. When it is desired to raise and lower the upper sash freely, the sash engaging member 13 is rendered inoperative by turning the lever 17, so that the block 19 is out of the way of the sash 11, and locking the rod 14 in position by means of the latches 25 and 27. It is evident that instead of attaching the latch to the lower sash it might equally well be secured to the upper sash so as to prevent movement thereof, or to any one of two adjacent members normally slideable relative to each other, and thus prevent relative movement in one direction.

In Fig. 7 a latch 28 is shown secured to a door 29 adjacent the floor 30 in such a way as to prevent swinging of the door 29 in one direction, when the latch is in operative position.

In Fig. 8 two latches 31 and 32 are secured at the top and bottom respectively of a barn door 33 shown as suspended from a track 34 in the well known manner. The latch 31 is adapted to engage the track 33 while the latch 32 engages the floor 35.

I claim as my invention:

1. A window latch comprising a housing

secured to one of two relatively movable members, a pivot rod extending through the housing, its ends projecting beyond the same, one end being slotted, a block in the form of a sector of a disk having a curved face and a straight face, and eccentrically mounted on the rod, a corrugated sash engaging strip secured to the curved face of the block, a spring reacting between the straight face of the block and the housing for normally holding the block in operative position, a lever rigid with one projecting end of the pivot rod for moving the block to inoperative position, a pivoted latch adapted to engage the slot in the other projecting end and a locking lug cooperating with the pivoted latch.

2. A latch comprising a housing secured to one of two relatively movable members, a sash engaging member being eccentrically pivoted within the housing and comprising a block in the form of a sector of a disk having a curved front face and a straight rear.

face having a recess therein, a corrugated sash engaging strip secured to the curved face of the block, and a coil spring reacting between the housing and said recess for holding the block in operative position, and means for moving the block to inoperative position.

3. A latch comprising a housing secured to one of two relatively movable members, a pivot rod extending through the housing, its ends projecting beyond the same and one end being slotted, a sash engaging member eccentrically mounted upon said rod, means for normally holding said member in sash engaging position, a lever secured to one projecting end of the pivot rod for moving said member to inoperative position, and means adapted to engage the slot in the other projecting end of the rod for locking the eccentrically mounted member in inoperative position.

JOHN J. BAHUZKY.
